UNITED STATES PATENT OFFICE.

JOSEPH A. DALRYMPLE, OF HAVERHILL, MASSACHUSETTS.

DESIGN FOR A SLIPPER ORNAMENT.

SPECIFICATION forming part of Design No. 33,538, dated November 13, 1900.

Application filed September 27, 1900. Serial No. 31,333. Term of patent 7 years.

To all whom it may concern:

Be it known that I, JOSEPH A. DALRYMPLE, a citizen of the United States, and a resident of Haverhill, in the county of Essex and State of Massachusetts, have invented and produced a new and original Design for a Slipper Ornament, of which the following is a full, clear, and exact description.

Reference is to be had to the accompanying drawings, forming a part of this specification, in which similar characters of reference indicate corresponding parts in both views.

Figure 1 is a face view of a slipper ornament, showing my design; and Fig. 2 is an enlarged section of the same on the line 2 2 in Fig. 1.

The design in its entirety consists of an ornamental casting having its face resembling intertwined strings of beads approximately

indicating the figure 8, with small loops at 20 the ends of the loops of the figure, the rear face of the casting appearing flat, with transverse perforations, as is plainly shown in Fig. 2.

The leading feature of the design consists 25 of an ornamental casting simulating beads.

Having thus fully described my invention, I claim as new and desire to secure by Letters Patent—

The design for a slipper ornament, as here- 30 in shown and described.

In testimony whereof I have signed my name to this specification in the presence of two subscribing witnesses.

JOSEPH A. DALRYMPLE.
